UNITED STATES PATENT OFFICE.

JOSEPH GEIGER, OF STEELTON, PENNSYLVANIA, ASSIGNOR, BY DIRECT AND MESNE ASSIGNMENTS, OF ONE-THIRD TO FRANK J. MARTER AND ONE-THIRD TO FRANK SNELL, BOTH OF STEELTON, PENNSYLVANIA.

COKE-OVEN-WALL CONSTRUCTION.

Application filed July 29, 1920, Serial No. 399,965. Renewed August 24, 1922. Serial No. 584,138.

To all whom it may concern:

Be it known that I, JOSEPH GEIGER, a citizen of Austria, residing at Steelton, in the county of Dauphin and State of Pennsylvania, have invented certain new and useful Improvements in Coke-Oven-Wall Constructions, of which the following is a specification.

This invention relates to coke oven wall 10 construction and more particularly to a coke oven of the Semet-Solvay type.

As heretofore constructed the walls of these ovens have presented the disadvantage that they have been liable to collapse especially in their upper portions due chiefly to the fact that the prior constructions have been such that the inner tiers of bricks, and particularly those immediately beneath the cap bricks, have not been provided with any 20 means for positively holding them in place. It is therefore one of the primary objects of the present invention to improve the wall construction of such an oven by providing for a locking connection or union between 25 the uppermost bricks of the inner tiers of the two walls of the oven and the cap bricks, so that the bricks of the inner tiers will not be liable to collapse.

Another object of the invention is to provide in such a wall construction, a novel 30 form of flue brick.

In the drawings:

Figure 1 is a vertical transverse sectional view through a coke oven of the Semet-Solvay type, the walls of the oven being constructed in accordance with the present invention;

Figure 2 is a top plan view of one of the flue bricks;

Figure 3 is a view in elevation of one end of the flue bricks;

Figure 4 is a similar view of the opposite end of the brick;

Figure 5 is a perspective view of one of the 45 bricks which go to make up the inner tier of each wall;

Figure 6 is a top plan view of the brick shown in Figure 5;

Figure 7 is a view similar to Figure 5,

illustrating one of the bricks which go to 50 make up the outer tier of each wall;

Figure 8 is a perspective view illustrating one of the flue bricks and a brick which is employed in connection therewith;

Figure 9 is a perspective view of one of 55 the cap bricks;

Figure 10 is a similar view of another one of the bricks;

Figure 11 is a similar view of still another brick employed. 60

The general arrangement and construction of the oven walls is best illustrated in Figure 1 of the drawings and in this figure the numeral 1 indicates in general the two side walls of the oven, the numeral 2 the cap 65 bricks of the walls, and the numeral 3 the arch bricks which span the space between the cap bricks and which constitute the top of the oven.

Each of the side walls 1 of the oven is of 70 hollow construction as usual so as to provide the combustion spaces 4, and each wall comprises an outer tier of bricks indicated in general by the numeral 5 and an inner tier indicated in general by the numeral 6. 75

Figure 10 of the drawings illustrates in perspective one of the bricks of the outer tier, this brick being indicated in general by the numeral 7 and having a flat or plane end 8 and provided in its opposite faces at its 80

opposite lateral edges with rabbets 9 providing tongues 10 adapting the bricks to be assembled with meeting lateral edges of adjacent bricks interlocking in a manner which will be readily understood. Also the other 85

end of each of the bricks 7 is rabbeted as at 11 to provide a projecting tongue 12. Figure 5 of the drawing illustrates one of the bricks of the inner tier 6, this brick being indicated in general by the numeral 13 and 90

having a square or plane lower end 14 and provided in one lateral edge with a longitudinally extending dove-tail groove 15 and at its opposite lateral edge with an outstanding dove-tail rib or tongue 16. The 95 upper end of this brick is rabbeted as at 17 thus providing an upstanding tongue 18, and the groove 15 and the tongue 16 each

extends for substantially one-half its respective width into the tongue 18. Of course, in assembling these bricks the tongues 16 of the bricks will fit into the groove 15 in the mating edges of adjacent bricks so that as in the case of the bricks 7, the bricks 13 are locked together as they are built up to form the wall. In placing the bricks 7 and 13 in position, they are placed on end and while 10 the ends 8 and 14 of the bricks 7 and 13 are referred to above as their lower ends, these ends in fact become the upper ends in some of the courses of the tiers 5 and 6. In order that this may be better understood as also 15 the purpose of the tongues 12 and 18 and rabbets 11 and 17, I will now describe the construction of the flue bricks and other bricks which are employed in the same relation as the flue bricks. Figures 2, 3, 4 and 8 20 of the drawings illustrate clearly the construction of one of the flue bricks, this brick being indicated in general by the numeral 19 and being provided substantially centrally with a flue opening 20. The body 25 of each brick is formed upon its upper and under sides with ribs 21 and 22. The ribs 21 and 22 extend at the opposite sides of the opening 20 and their opposing faces constitute extensions of the walls of this opening, the rib 21 being located parallel to that edge of the brick 19 which is to be the outer edge when the brick is in place within the wall of the oven, and the rib 22 being located parallel to the edge of the brick which is to 30 be the inner edge when the brick is in place. One end of the brick 19 is indicated by the numeral 23 and the ends of the ribs 21 and 22 terminate, at this end of the brick, substantially in transverse alignment with the 35 adjacent or corresponding end wall of the opening 20, their said ends being free from connection with each other. At their other ends, however, the ribs 21 and 22 are connected by a portion 24 which is extended, as 40 indicated by the numeral 25, to the extreme corresponding end of the body of the brick both at the upper and under faces thereof. The flue bricks 19 are interposed between the course of the bricks 7 and 13 comprising 45 the tiers 5 and 6, the rabbets 11 and 17 of the said bricks 7 and 13 fitting the ribs 21 and 22 of the flue bricks and the said bricks 7 and 13 being disposed in relatively inverted positions in adjacent courses of the 50 tiers so that in the lowermost course in each wall 1 shown in Figure 1 of the drawings, the squared lower ends 8 and 14 of the bricks 7 and 13 are lowermost and the rabbets 11 and 17 fit the ribs 21 and 22 upon the under 55 sides of the flue bricks which are disposed upon their upper ends, and in the next course above, the said bricks 7 and 13 are inverted with relation to the bricks of the lower course so that their rabbets 11 and 17 then 60 fit the ribs 21 and 22 upon the upper sides 65 of the flue bricks. In addition to the flue bricks 19 there are employed other bricks indicated in general by the numeral 26 and one of which is clearly shown in Figure 11, and these latter bricks are of the same general form as the bricks 19 except that they are devoid of the openings 20 and are therefore closed from end to end, being formed, however, thicker at their central portions than at their marginal portions so as to provide bosses 27 upon their upper and under faces and thus form shoulders against which the edge portions of the squared ends 8 and 14 of the bricks 7 and 13 may engage. In building up the walls, the bricks 19 and 26 70 in each course are alternately arranged, and where the ends 23 of the bricks 19 occur, bricks indicated by the numeral 28 are arranged transversely with relation thereto so as to span the space between the ribs 21 and 22 and the bricks 7 and 13 and thus form the required flues for the combustion products. 75 Each tier 5 and 6 of each wall may comprise, of course, any desired number of courses but the arrangement is always such that the uppermost bricks 7' and 13' will be provided at their upper ends with tongues which are indicated respectively specifically by the numerals 29 and 30, these tongues being fitted into grooves 31 and 32 formed in 80 the under sides of the cap bricks 2. In this manner a lock is provided between the upper ends of the bricks 7 and 13 comprising the uppermost courses of the tiers, and the respective cap bricks 2 and thus I provide against collapse of this portion of the walls, which is the portion first to give way 85 in the ordinary oven wall construction. 90 The arch brick 3 is rabbeted at its opposite ends in its under face as at 33 to fit the 105 adjacent upper corners of the cap bricks 2. It will be understood by those skilled in the art that by the use of each one of the flue bricks 19, I am enabled to avoid the employment of six or more separate bricks 110 which are at the present time made use of in forming the flue passages. 115 It is preferable that the blocks 26 shown in Figure 11 of the drawings be formed in their opposite ends and opposite faces with rabbets 34 so that wherever two of these blocks meet end to end in the construction of the oven wall, a lap joint will be formed. 120 Having thus described the invention, what is claimed as new is:

1. In coke oven wall construction, spaced inner and outer tiers of bricks arranged in courses, and flue bricks disposed between the courses and each provided with an opening and at opposite sides of the opening with ribs for engagement with the abutting ends of the first mentioned bricks, the said ends of the first mentioned bricks being rabbeted to receive the ribs. 125
2. A flue brick for a coke oven wall con- 130

struction comprising a body having an opening therethrough, the body being formed at opposite sides of the opening with ribs and with a portion extending between corresponding ends of the ribs.

3. A flue brick for a coke oven wall construction comprising a body having an opening therethrough, the body being formed at

opposite sides of the opening with ribs and with a portion extending between corresponding ends of the ribs, the other ends of the ribs being unconnected and terminating substantially in transverse alignment with the corresponding end wall of the opening.

In testimony whereof I affix my signature, 15
JOSEPH GEIGER. [L. S.]
